US00D998627S

(12) United States Design Patent (10) Patent No.: US D998,627 S
Brown et al. (45) Date of Patent: * Sep. 12, 2023

(54) DISPLAY SCREEN OR PORTION THEREOF
WITH A GRAPHICAL USER INTERFACE

5,364,100 A 11/1994 Ludlow et al.
5,449,173 A 9/1995 Thomas et al.
5,531,441 A * 7/1996 Dabrowski G07F 17/3293
463/13

(71) Applicant: IGT, Las Vegas, NV (US)

5,542,669 A * 8/1996 Charron G07F 17/3244
463/13

(72) Inventors: Bradford Brown, Sparks, NV (US);
David Howe, Reno, NV (US)

(73) Assignee: IGT, Las Vegas, NV (US)

() Term: 15 Years

(21) Appl. No.: 29/797,601

(22) Filed: Jul. 1, 2021

Related U.S. Application Data

(63) Continuation of application No. 16/052,240, filed on Aug. 1, 2018, now Pat. No. 11,074,776, which is a continuation of application No. 15/273,119, filed on Sep. 22, 2016, now Pat. No. 10,049,526.

(57) CLAIM

The ornamental design for a display screen or a portion thereof with a graphical user interface, as shown and described herein.

DESCRIPTION

The FIGURE is a front view of a display screen or a portion thereof with a graphical user interface of our new design. The dashed broken line perimeter in the drawing illustrates a display screen or portion thereof and forms no part of the claimed design. The remaining dashed broken lines in the drawing illustrate portions of the graphical user interface that form no part of the claimed design.
